ELECTRIC SOCKET

Filed Dec. 10, 1942

UNITED STATES PATENT OFFICE

2,360,444

ELECTRIC SOCKET

Leo Pollock, New York, N. Y.

Application December 10, 1942, Serial No. 468,455

11 Claims. (Cl. 173—340)

This invention relates to electric sockets. More particularly the invention pertains to electric sockets which are adapted to receive threaded electric plugs and the like.

The primary object of the invention is to provide a socket of the character described which consists of a minimum of simple, easily fabricated parts, can be produced at high speed and on a large scale by unskilled workers, is so constructed that very few and simple operations are required for assembly, can be connected with ease in an electric circuit during assembly, and can be produced at a lower cost than any previously marketed socket.

Another object of the invention is to provide a socket of the character described which will appreciably reduce the cost of fabricating and assembling series and parallel Christmas tree ornamental lighting outfits.

A further object of the invention is to provide a socket of the character described which employs an improved and simplified construction to eliminate the metal screw shell heretofore commonly employed in sockets.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawing, in which are shown various possible embodiments of this invention, and wherein like numbers refer to like parts throughout,

Fig. 1 is a side view of a socket embodying my invention, with a conventional Christmas tree bulb wired in a parallel circuit;

Fig. 2 is an enlarged sectional view thereof, taken substantially along the line 2—2 in Fig. 1;

Fig. 3 is a sectional view taken substantially along the line 3—3 in Fig. 2;

Fig. 4 is a sectional view taken substantially along the line 4—4 in Fig. 3;

Fig. 5 is a partially exploded view of the socket in perspective;

Fig. 6 is a perspective view of one of the contact elements wired for connection in a series circuit; and

Fig. 7 is a fragmentary view, similar to Fig. 2, of a socket embodying a modified form of my invention.

In general I accomplish the objects of the invention by providing an insulating housing

which is split into two halves along a plane passing through the axis of symmetry of the housing. The two halves are provided with mating recesses of different sizes and shapes which cooperate to form a screw thread for receiving a bulb and a plurality of apertures for receiving and firmly holding simple contact elements. A resilient annular element also may be provided to facilitate electric contact with the screw shell of the bulb, this additional element being similarly held in place by the mating recesses.

Referring now in detail to the drawing, and more particularly to Figs. 1—5, 10 designates an electric socket constructed in accordance with my invention. The socket is adapted to form part of a Christmas tree lighting outfit and to receive the threaded plug portion of a conventional electric lamp, such, for example, as a Christmas tree bulb 12. A pair of conductor cables 14, comprising twisted copper strand cores 16, insulating rubber sheaths 18, and braided fabric covers 20, electrically and physically connect the socket, in a manner later described, in a parallel Christmas tree lighting outfit.

The socket comprises a housing 22 of hard rubber, "Bakelite," or similar insulating material in which there are contained two identical electrically conductive contact elements 24, 26 and an electrically conductive contact ring 28.

30 The contact elements 24, 26 are formed from flat stock of a suitable resilient, electrically conductive material, like phosphor bronze, in such fashion as to provide a shank 29 and a unitary tip 30. One lateral edge of the shank is recessed to provide a deep U-shaped indentation 32 (Fig. 3) which is adapted to snugly and fully receive a conductor cable 14. The other lateral edge of the shank is recessed in alignment with the first indentation 32. The second indentation, thus provided, is in the form of a W, and, in effect, comprises symmetrically disposed twin indentations 34, separated by a slender barrier 36 whose free end is pointed so that said barrier can serve as a piercing tine. The bottoms of the twin indentations 34 are each large enough to accommodate about half the diameter of a cable 14 but their mouths, adjacent the tip of the barrier, are less than half such diameter so that when a cable is impaled upon the barrier and forced into the twin indentations, a part of the cable will remain squeezed in said mouths. The top of the W-shaped indentation is as wide as the diameter of a cable so that when a cable is inserted therein it will be so guided as to be diametrically pierced by the barrier.

The lateral edges of the shanks above the deep indentations 32, 34 are recessed to provide shallow positioning notches 38 which need not be in alignment with each other.

Near the base of the shank deep transverse aligned slits 40 are cut to form two oppositely extending fingers 42. These fingers are bent to a position perpendicular to the plane of the shank and parallel to and spaced from each other. As will later be made clear, said fingers 42 are provided for use as strain relievers in the event that the socket 10 is series-connected in a Christmas tree lighting outfit.

The tips 30 of the contact elements each comprise a branch 44 which extends horizontally from the top of the shank 29, an integral wall 46 which extends vertically upwardly from the end of the branch, and a plane contact leg 48 which extends horizontally from the top of the wall 46 to which it is integrally connected. The leg 48 and branch 44 are substantially parallel and form with the wall 46 a U-shaped tip whereof the leg 48 is longer than the branch 44. This construction permits the leg 48 to be resiliently depressed and is of particular advantage when a contact element is used as the center post of the socket 10.

The contact ring 28 is formed from flat stock of a suitable resilient, electrically conductive material, like phosphor bronze, in such fashion as to provide a split annulus of flat cross-section. The annulus is deformed into a one turn helix of small pitch. The interior diameter of the helix is slightly greater than the smallest diameter of the lower inturned portion of the brass screw shell 50 at the base of the electric bulb 12.

The housing 22 includes two substantially similar halves 52, 54 which, in assembly of the socket, are adapted to be disposed in registry and abutment along a plane including the axis of symmetry of the socket.

Due to the close similarity between the two halves, only the left hand half 52 will be described and the difference between the two halves later pointed out. For convenience, elements of the left hand half 52 will be identified by unprimed reference numerals and like elements of the right hand half 54 by like primed reference numerals.

The half 52 is substantially semi-cylindrical, the flat surface 56 thereof being adapted to abut the flat surface 56' of the other half 54. The upper part of the half 52 is provided with a central recess 58 having a flaring portion 60. Below this flared portion the recess 58 is formed into a series of sloping ridges 62 which cooperate with ridges 62' in the same zone of the half 54 to provide a female screw thread in which the screw shell 50 of the electric bulb 12 can be threaded.

It will be noted that because the two halves 52, 54 have their ridges 62, 62' disposed on opposite sides of the screw shell 50 that said ridges are right and left hand halves respectively of a screw thread and are not, therefore, located in identical positions in the two housing halves 52, 54. This constitutes the basic difference between said housing halves.

Below the ridged portion 62 the recess 58 communicates with a semi-cylindrical pocket 64 of sufficient diameter and height to accommodate the helical contact ring 28.

A recess 66 lies below and communicates with the pocket 64 at the periphery thereof. This recess is of proper size and shape to receive one

lateral half of a contact element tip 30 (Fig. 5) with the branch 44 resting on the base of the recess and the contact leg 48 touching a portion of the ring 28 (Fig. 2).

5 A slot 70 extends downwardly from the center of the recess 66 and is of such dimensions as to freely accommodate one lateral half of a contact element shank between the tip 30 and the indentations 32, 34. Nibs 72 project from the 10 sides of the slot 70 adjacent the lateral edges of the shank and are adapted to be received in the shallow shank notches 38 whereby to anchor the contact elements when the two halves of the socket are assembled.

15 The slot 70 terminates at a passageway 74 which runs transversely through the socket and accommodates the two conductor cables 14. Said passageway 74, adjacent the outer surface of the socket, is just of sufficient size to receive one of the conductor cables. Beneath the slot 70, however, the passageway is enlarged, as at 20 76, in order to accommodate both the conductor wire 14 and the fingers 42 of a contact element 24 which, it will be remembered, are disposed perpendicular to the shank 29. Said passageway is enlarged enough to permit the base of the contact element 24 to rest thereon when the branch 44 of the contact element tip rests upon the bottom of the recess 66. Said enlarged passageway portion 76 is provided with a nib 78 adapted to project into the mouth of one of the 25 indentations 32, 34 when the contact element is disposed in the socket half 52 and thus prevent the cables 14 from shifting.

30 The foregoing series of recesses and elements 66-78 may be duplicated on the other side of the socket halves 52, 54 to facilitate assembly of the socket by permitting the lateral contact element 24 to be disposed to either side of the center contact element 26.

35 Another series of recesses, slots and passageways similar to that just described for the lateral contact element 24 is provided at the center of the socket half 52 to receive and hold the center contact element 26. Said series includes a recess 80 similar to the recess 66 but having its bottom surface disposed lower than the bottom surface of said recess 66. This is done in order to enable the contact leg 48 of this element to engage the low central contact 82 of the electric bulb 12 when the same is screwed into the socket 10. A slot 84 connects the recess 80 with the conductor passageway 74. The passageway is enlarged at 86 beneath the slot 84 and to both sides of the plane thereof in order to be able to accommodate the projecting fingers 42 of a contact element regardless of which way the element is facing.

40 It will be noted that the said enlarged portion 86 has its bottom disposed below the bottom of the enlarged portion 76 due to the fact that the central contact element 26 is lower in the socket than the lateral contact element 24.

45 The slot 84 and enlarged portion passageway 86 have nibs 72 and 78 similar to those in the slot 70 and enlarged passageway portion 76. The passageway 74 intermediate the two enlarged portions 76 and 86 is downwardly inclined (Figs. 2 and 5) so as to receive the conductor cables 14 which, as soon will be seen, slope in this portion of the socket.

50 When the two halves are assembled in registered relationship, the several recesses and slots hereinabove described will cooperate to form

apertures which house and firmly hold the two contact elements 24, 26 and the contact ring 28.

Suitable means are provided to hold the socket in such assembled relationship. Such means may comprise oppositely disposed, apertured ears 83 at the plane surfaces 56, 56' of each socket half 52, 54 which are adapted to have eyelets 90 received therein when the socket is assembled.

I may prevent seepage of dirt and moisture through the crack separating the two socket halves 52, 54 by providing a seal comprising a groove G around the periphery of one of the halves 52 and a mating ridge R around the periphery of the other half 54.

To enhance the appearance of the socket, the outer surface thereof may be indented to conform to the inner flare 60 immediately above the screw threaded portion.

The socket 10, having the various elements thereof constructed in the foregoing manner, can be easily assembled and connected in a parallel circuit as follows:

Each conductor cable 14 is forced into a W-shaped indentation in a different contact element 24, 26 so that the tine 36 pierces the stranded wire core 16, pairs of contact elements which are to be disposed in a socket being so arranged that their U-shaped tips 30 are oppositely faced. With this arrangement, when the cables are brought into parallel closely spaced relationship the cable which is impaled upon a tine 36 of one contact element will be received in the U-shaped indentation 32 of the other contact element. The contact elements are now arranged with their shanks spaced apart a distance equal to the spacing between the slots 70, 84 in the housing halves. Next, the contact elements and conductor cables are inserted in one of the halves, for example, the half 54, as shown at the right hand side of Fig. 5 and the split contact ring 28 inserted in the semi-cylindrical pocket 64 of the other of said halves 52, as shown at the left hand side of Fig. 5. Finally, the two halves are brought together and the eyelets 90 passed through the apertures in the ears 88 and the ends of the eyelets spun over.

If it is desired to place the socket in a series circuit the assembly operation is slightly varied, and is carried out as follows: A plurality of short conductor cables 92 (Fig. 6) are made of fixed length, determined by the distance the bulbs are to be spaced apart. The two ends of each short cable are placed between the fingers 42 of a contact element and said fingers clinched to anchor the short cable lengths to the elements and take up any strain imposed upon the cable 90 after the socket has been assembled. The cable is then sharply bent adjacent the end and forced into the W-shaped indentation where electrical contact with the element is made by the tine 36. A pair of elements, each from a different cable, are then inserted in one of the socket halves. If the series circuit is to be in the form of a loop, the other half of the socket may now be mounted and the eyelets 90 inserted and spun. If, however, it is desired to have the series circuit in the form of a string, like a parallel circuit, a return cable for the circuit is passed through each socket. To facilitate insertion of the return cable, the contact elements with the short cable attached can be placed in the socket halves with both W-shaped indentations concealed and both U-shaped indentations, which accommodate the return cable, exposed. The re-

turn cable is held in place against accidental dis-arrangement by the nib 78.

If desired, my novel socket can employ conventional binding posts for making electric connections in lieu of tines 36, and in Fig. 7 I have shown a socket 94 embodying my invention which is adapted to make use of this latter form of connection. Said socket differs from the socket 10, illustrated in Figs. 1-5 only by slight variations in the contact element and socket halves. The contact elements 96, 98 have no slits 40, fingers 42, tines 36, or indentations 32, 34 therein as do the elements 24, 26. Instead there is provided an annular tapped boss 100 on each contact element in which a binding post 102 is threaded. The elements 96, 98 are in all other respects similar to the elements 24, 26. The socket halves 104, in which the contact elements 96, 98 are received, have bottom apertures 106, 108 to pass conductor cables 110, 112 attached to the binding posts. These halves have no nibs 78 but, save for the absence of said nibs and the provision of the apertures 106, 108, are similar to the socket halves 52, 54 illustrated in Figs. 1-5. The cable passageway 74 may be left in the halves 104 to simplify moulding and, if required, plugged with insulating material after assembly of the socket 94.

It will thus be seen that there is provided a device which achieves the several objects of this invention, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A socket comprising a housing of insulating material, said housing including two halves abutted along a plane passing through the axis of symmetry of said socket, said halves having mating ridged recesses which cooperate to form a female thread and mating recesses which cooperate to form apertures, and contact elements and a contact ring received and firmly held in said apertures beneath said thread, said ring having a smaller inner diameter than that of the socket at the tips of the thread, said apertures being so arranged that one of said contact elements bears against said contact ring.

2. A socket comprising a housing of insulating material, said housing including two halves abutted along a plane passing through the axis of symmetry of said socket, said halves having mating ridged recesses which cooperate to form a female thread and mating recesses which cooperate to form apertures, and contact elements and a contact ring received and firmly held in said aperture beneath said thread, said ring having a smaller inner diameter than that of the socket at the tips of the thread, said apertures being so arranged that one of said contact elements bears against said contact ring, said ring being electrically insulated from the other of said contact elements, said other contact element being disposed diametrically and symmetrically of and below said contact ring.

3. A socket comprising a housing of insulating material, said housing including two halves abutted along a plane passing through the axis

of symmetry of said socket, said halves having mating ridged recesses which cooperate to form a female thread, and mating recesses which cooperate to form apertures, and a pair of contact elements and a contact ring received and firmly held in said apertures, each of said contact elements having an offset resilient tip portion, said apertures being so arranged that the tip portion of one of said elements bears against said contact ring and the tip portion of the other of said elements is disposed centrally of and below said contact ring, said ring being electrically insulated from said other element.

4. A socket as set forth in claim 3 wherein the inner diameter of the ring is smaller than the diameter of the socket at the tips of the thread.

5. A socket as set forth in claim 3 wherein the ring is helical and has a smaller inner diameter than that of the socket at the tips of the thread.

6. A socket as set forth in claim 3 wherein the ring is helical and has a pitch differing from that of the thread.

7. A socket comprising a housing of insulating material, said housing including two halves abutted along a plane passing through the axis of symmetry of said socket, said halves having mating ridged recesses which cooperate to form a female thread, and mating recesses which cooperate to form apertures, and a pair of contact elements received and firmly held in said apertures, the lateral edges of said contact elements having shallow indentations therein and the mating recesses of said halves having nibs therein which are received in said shallow indentations to anchor said elements.

8. A socket comprising a housing of insulating material, said housing including two halves abutted along a plane passing through the axis of symmetry of said socket, said halves having mating ridged recesses which cooperate to form a female thread, and mating recesses which co-

operate to form apertures, and a pair of contact elements received and firmly held in said apertures, a lateral edge of each contact element having a deep indentation therein to receive conductor cables for electrically connecting the socket in an electrical circuit, and the mating recesses of the halves having nibs which project into the mouths of said indentations to prevent the cables from shifting.

9. A socket comprising a housing of insulating material, said housing including two halves abutted along a plane passing through the axis of symmetry of said socket, said halves having mating ridged recesses which cooperate to form a female thread, and mating recesses which cooperate to form apertures, and a pair of contact elements received and firmly held in said apertures, each lateral edge of each contact element having a deep indentation therein to receive conductor cables for electrically connecting the socket in an electrical circuit, and the mating recesses of the halves having nibs which project into the mouths of said indentations to prevent the cables from shifting.

10. A socket as set forth in claim 9 wherein an indentation in one of the lateral edges of each contact element has a piercing tine in registration with the nib projecting into the mouth of the indentation.

11. A socket comprising a housing of insulating material, said housing including two halves abutted along a plane passing through the axis of symmetry of said socket, said halves having mating ridged recesses which cooperate to form a female thread, and mating recesses which cooperate to form apertures, and a pair of contact elements received and firmly held in said apertures, each of said contact elements having a threaded aperture therein in which a binding post is received.

LEO POLLOCK.
